UNITED STATES PATENT OFFICE.

ALEXANDER MARR, OF MANCHESTER, ENGLAND.

SOUND-TRANSMITTING INSTRUMENT.

Application filed April 5, 1921. Serial No. 458,810.

To all whom it may concern:

Be it known that I, ALEXANDER MARR, a subject of the King of Great Britain and Ireland, and a resident of Manchester, in the county of Lancaster, England, have invented certain new and useful Improvements in or Relating to Sound-Transmitting Instruments, of which the following is a specification.

10 This invention relates to sound transmitting instruments such as e. g. telephone transmitters or microphones, gramophone record producers, dictating machines, car trumpets and the like, of the kind wherein the mouthpiece or part whereby the sound waves are led to the diaphragm or equivalent of the instrument or the ear, is in the form of a concentrator chamber having a constricted aperture for the entrance of the

20 sound waves.

25 The object of the invention is to provide an improved arrangement of concentrator mouthpiece or the like whereby the sound waves entering same are conveyed in greater amplitude to the diaphragm or equivalent or the tympanum of the ear with corresponding greater clearness in sound reproduction.

According to the invention, there is provided in the concentrator mouthpiece or the like at or about the point of greatest width a partition and the sound waves entering the constricted inlet aperture are compelled to pass said partition by a passage or a plurality of passages arranged outside of or beyond the periphery of the constricted inlet aperture, and area or the collective area of which is not less than the area of said aperture. Further, according to this invention, I may in some cases provide the concentrator mouthpiece or the like with a tapered or coned exit, or fit in or at the exit thereof a hollow truncated cone having its smaller ear or apex directed rearwardly, and said tapered or coned exit or cone may in some cases be surrounded by an annular space.

30 In the accompanying drawing, Fig. 1 is a section of one embodiment of the invention in a telephone transmitter, the exit of the mouthpiece of which is at right angles to the inlet thereto, and Fig. 2 is a plan of Fig. 1 with one half of the concentrator cap of the mouthpiece cut away. Fig. 3

35 is a section illustrating an embodiment of the invention in the present day standard

mouthpiece for telephone transmitters, dictating machines and other sound transmitting instruments. Figs. 4 and 5 are fragmentary sections illustrating modifications 60 of the embodiment shown in Fig. 3. Figs. 6 and 7 are fragmentary views partly in elevation and partly in section of the exit end of a sound wave concentrator for use with the ear. Fig. 8 is a fragmentary section showing a modification of the exit end of the concentrator mouthpiece illustrated in Fig. 1. In the drawings and the following description, like characters of reference indicate like parts.

Referring first to Fig. 1, 2 is the mouthpiece of the transmitter, 3 the diaphragm, 4 the resistance varying cell and 5 the casing enclosing the diaphragm and cell.

70 To the inlet of the mouthpiece 2 is fitted 75 a concentrator cap 6 dished or concaved on its inner face 7 and provided with a constricted aperture 8 for the entrance of sound waves. Between the cap 6 and the mouthpiece 2, i. e., at the widest part of the concentrator chamber constituted by the mouthpiece and cap, I arrange a partition 9 of metal, vulcanite or other appropriate material, provided with perforations 10. The latter are arranged near the periphery of 80 the partition so that they do not lie in line with the entrance aperture 8 but lie outside or beyond the periphery of such aperture. The perforations 10 are such in number and size that their collective area is not 85 less than the area of the aperture 8. The arrangement is preferably also such that the area of the aperture 8 is approximately one fourth of the area of the widest part 90 of the concentrator chamber whereat the 95 partition 9 is arranged; the distance of the aperture 8 from the partition is approximately one fourth of the diameter of the latter; and the radius of the wall of the dished underside of the cap 6 is approximately 100 equal to the distance of the aperture 8 from the partition.

The exit of the concentrator mouthpiece, which is at right angles to the inlet thereto, 105 is fitted in a ferrule 11 or equivalent on or in the casing 5 so that it lies close to the diaphragm 3. Within the exit end of the concentrator mouthpiece is fitted a hollow truncated cone 12 of metal, vulcanite or other appropriate material having its apex 110 or smaller end opening to the diaphragm 3, and surrounded by an annular space 13

bounded by the exterior surface of the cone and the interior surface of the end of the mouthpiece.

With the arrangement of perforated partition 9 described above, it is found that the sound waves entering the aperture 8 and passing through the perforations 10 pass along the wall of the mouthpiece to the cone 12, whence they issue to act upon the diaphragm 3, and that such surface conduction of the sound waves results in a better transmission of the sound waves to the diaphragm with a better action of the waves on the diaphragm and corresponding greater distinctness in reproduction of the sounds. The cone 12 condenses or concentrates the sound waves on the diaphragm and the surrounding annular space 13 serves as an expansion chamber for the sound waves rebounding from the diaphragm, thereby preventing such waves from interfering with the waves issuing from the cone, which also results in a better action of the sound waves on the diaphragm and greater distinctness in reproduction.

Instead of the cone 12 lying within the end of the concentrator mouthpiece 2, it may be made integral with said end, as shown in Fig. 8, or may extend therebeyond, as shown in Fig. 6, in which cases the annular space 13 will, as shown in Fig. 8, be formed between the exterior surface of the cone and the interior surface of the ferrule 11 or equivalent into which the end of the mouthpiece is fitted.

In Fig. 3 the concentrator cap and perforated partition are shown applied to the standard mouthpiece in which the exit is in line with the entrance. The arrangement of the cap and perforated partition and the relative proportions of the areas of the aperture 8 partition 9 and perforations 10 are preferably as above described. As the moisture of the breath will condense and deposit on the partition 9 the grid 14 usually provided at the inner end of mouthpieces of this type may be dispensed with without fear of said moisture reaching and affecting the diaphragm. The inner or exit end of this form of concentrator mouthpiece may also be fitted with a cone lying within the end as in Fig. 1, or projecting therebeyond as in Fig. 6, or be formed with a tapered or coned end as in Fig. 8 so that when the mouthpiece is fitted to the casing of the instrument the annular space 13, Fig. 1, results.

Instead of the perforated partition 9 being flat as illustrated in Figs. 1 and 3, the face thereof next the aperture 8 may be convex as in Fig. 4, or concave as in Fig. 5.

The sound wave concentrator provided with a perforated partition as above described may be used by the partially deaf, and in such case the device preferably takes

the form of the concentrator mouthpiece shown in Fig. 1, and has its end provided with a projecting cone as in Fig. 6, or tapered or coned as in Fig. 8 for insertion into the ear, or has its said end provided with a flange 15 or the like, as shown in Fig. 8, for holding against the ear.

What I claim and desire to secure by Letters Patent is:—

1. A sound wave concentrator comprising a mouth piece having a constricted opening for the entrance of sound waves and walls, first divergent from the opening and then convergent towards the exit end, a partition having a substantially flat surface arranged across the interior of the mouth piece at the junction of the divergent and convergent walls, said partition being imperforate at its central portion and apertured at its outer annular portion, the area of said opening at the entrance end being approximately one-fourth the area between the walls at the junction of the divergent and convergent walls.

2. A sound wave concentrator comprising a mouth piece having a constricted opening for the entrance of sound waves and walls, first divergent from the opening and then convergent towards the exit end, a partition arranged across the interior of the mouth piece at the junction of the divergent and convergent walls, said partition being imperforate at its central portion and apertured at its outer annular portion, the distance between the constricted opening and the partition being approximately one-fourth the diameter of the latter.

3. A sound wave concentrator comprising a mouth piece having a constricted opening for the entrance of sound waves and walls, first divergent from the opening and then convergent towards the exit end, a partition arranged across the interior of the mouth piece at the junction of the divergent and convergent walls, said partition being imperforate at its central portion and apertured at its outer annular portion, the divergent wall being curved with a radius approximately equal to the distance from the constricted opening to the partition.

4. A sound wave concentrator comprising a mouth piece having a constricted opening for the entrance of sound waves and walls, first divergent from the opening and then convergent towards the exit end, a partition arranged across the interior of the mouth piece at the junction of the divergent and convergent walls, said partition being imperforate at its central portion and apertured at its outer annular portion, the area of said opening at the entrance end being approximately one-fourth the area between the walls at the junction of the divergent and convergent walls, the distance between the constricted opening and the partition

being approximately one-fourth the diameter of the latter.

5. A sound wave concentrator comprising a mouth piece having a constricted opening for the entrance of sound waves and walls, first divergent from the opening and then convergent towards the exit end, a partition arranged across the interior of the mouth piece at the junction of the divergent and convergent walls, said partition being imperforate at its central portion and apertured at its outer annular portion, the area of said opening at the entrance end being approximately one-fourth the area between the walls at the junction of the divergent and convergent walls, the divergent wall being curved with a radius approximately equal to the distance of the constricted opening to the partition.

20 6. A sound wave concentrator comprising a mouth piece having a constricted opening for the entrance of sound waves and walls, first divergent from the opening and then convergent towards the exit end, a partition arranged across the interior of the mouth piece at the junction of the divergent and convergent walls, said partition being imperforate at its central portion and apertured at its outer annular portion, the area of said opening at the entrance end being approximately one-fourth the area between the walls at the junction of the divergent and convergent walls, the distance between the constricted opening and the partition being approximately one-fourth the diameter of the latter, the divergent wall being curved with a radius approximately equal to the distance of the constricted opening to the partition.

40 7. A sound wave concentrator comprising a mouth piece having a constricted opening for the entrance of sound waves and walls, first divergent from the opening and then convergent towards the exit end, a partition arranged across the interior of the mouth piece at the junction of the divergent and convergent walls, said partition being imperforate at its central portion and apertured at its outer annular portion, the collective area of the apertures in the partition being not less than the area of the constricted opening.

8. A sound wave concentrator comprising a mouth piece having a constricted opening for the entrance of sound waves and walls, first divergent from the opening and then convergent towards the exit end, a partition arranged across the interior of the mouth piece at the junction of the divergent and convergent walls, said partition being imperforate at its central portion and apertured at its outer annular portion, the collective area of the apertures in the partition being not less than the area of the constricted opening, the area of said opening at the entrance end being approximately one-fourth the area between the walls at the junction of the divergent and convergent walls.

9. A sound wave concentrator comprising a mouth piece having a constricted opening for the entrance of sound waves and walls, first divergent from the opening and then convergent towards the exit end, a partition arranged across the interior of the mouth piece at the junction of the divergent and convergent walls, said partition being imperforate at its central portion and apertured at its outer annular portion, the collective area of the apertures in the partition being not less than the area of the constricted opening, the distance between the constricted opening and the partition being approximately one-fourth the diameter of the latter.

10. A sound wave concentrator comprising a mouth piece having a constricted opening for the entrance of sound waves and walls, first divergent from the opening and then convergent towards the exit end, a partition arranged across the interior of the mouth piece at the junction of the divergent and convergent walls, said partition being imperforate at its central portion and apertured at its outer annular portion, the collective area of the apertures in the partition being not less than the area of the constricted opening, the divergent wall being curved with a radius approximately equal to the distance of the constricted opening to the partition.

In witness whereof I have hereunto set my hand.

ALEXANDER MARR.
